UNITED STATES PATENT OFFICE.

GEORGE M. FITZPATRICK, OF MILFORD, MASSACHUSETTS, ASSIGNEE OF ONE-HALF TO
JOHN J. TULLY, OF MILFORD, MASSACHUSETTS.

STEAMING DEVICE FOR STEAMING THE TIPS OR BOXES AND VAMPS OF BOOTS AND
SHOES.

1,132,518.

Specification of Letters Patent. Patented Mar. 16, 1915.

Application filed May 2, 1914. Serial No. 836,044.

To all whom it may concern:

Be it known that I, GEORGE M. FITZPATRICK, a citizen of the United States, and a resident of Milford, county of Worcester, 5 State of Massachusetts, have invented an Improvement in Steaming Devices for Steaming the Tips or Boxes and Vamps of Boots and Shoes, of which the following description, in connection with the accompanying drawing, is a specification, like characters on the drawing representing like parts.

In the manufacture of boots and shoes it is necessary to soften or make pliable the material or stock that comprises the box, (commonly called the box toe), and the vamps. Various means have been devised for making pliable this material, involving the erection of a separate steaming device, in which 15 steam is conducted, and the placing within of that part of the shoe containing the stock sought to be made pliable, thereby necessitating a separate motion or operation, compelling the operator to handle the shoe two 20 or more times, waiting until the steaming device accomplishes its function, removing the shoe therefrom and then proceeding with the next operation.

My present invention has for its object 30 the production of simple, novel and efficient means for softening and making pliable the stock or material that comprises the box, toe or vamp, while the shoe is in the machine upon which the operator is working, enabling the operator to soften the stock in 35 question while operating on another part of the shoe.

In accordance with my invention the operator places the shoe in a heel and toe lasting machine for the purpose of lasting the heel and toe, and while operating on the heel, commonly called the heel-seat, by my invention he is enabled to soften and make pliable the stock in question, commonly 45 called "steaming the toe," at the same time; and when he finishes his operation on the heel-seat, by means of my invention, the toe is then in condition to enable him to immediately last the toe.

I believe that it is a distinct novelty in 50 the process of making boots and shoes, to apply softening means to the toe portion to prepare the toe and box for the lasting operation, while permitting, simultaneously, the

operator to work at some other operation on 55 the shoe. My novel process thus is a great time saver, and furthermore, when employed in the shoe lasting machines such as the well-known "Chase" laster or "Ideal" laster, or No. 5- bed laster, the box toe can 60 be subjected to the softening operation immediately preceding lasting of the toe and during the lasting of the heel. The apparatus for carrying out this process, however, is not limited to use with any one type 65 of machine, nor, merely, with lasting machines, but lends itself readily to cooperate with several different shoe machines and it will readily occur to those skilled in the art to use the same in connection with many 70 other shoe machines, where a softening or "tempering" is requisite.

The apparatus herein illustrated constitutes a preferred form for carrying out the process, and also includes a novel form of 75 steam separator, but neither the process above briefly outlined, nor the particular type of steam separator is herein claimed specifically, the subject matter thereof being reserved for other applications, this application being directed to the applying or spraying apparatus.

The various novel features of my invention will be fully described in the subjoined specification and particularly pointed out in 85 the following claims.

Figure 1, is a side elevation of a preferred embodiment of my invention. Fig. 2, is a view of the top of the device shown in 90 Fig. 1.

In the drawings, A represents a steam conveying pipe with a regulating valve B, and C is a pipe conducting steam from the regulating valve B, into a steam separator having chambers D, and F, formed by 95 means of a partition Q, substantially as shown in Fig. 1. A passage E is provided from the chamber D, to the chamber F, a short distance from the bottom of the separator, around the end of the partition Q. 100

When the steam enters the chamber D, it contains more or less moisture and this moisture when it strikes the partition Q, drops to the bottom of the separator, there condensing and collecting in a pipe M, from 105 whence it may be drained, by opening the valve N, to the waste pipe O. The dry steam flows on through the passage E, and

thence rises upward into the chamber F, thence through a swivel joint G, into an outside tube formed as a telescopic extension joint through a pipe H, thence into a smaller pipe I, which slides in the pipe H, and a steam tight joint is provided by the packing nut L. A second swivel joint J, connects the applying form K, with the pipe I, and this applying form K is perforated on the lower side with several small holes through which the steam is conveyed directly to the part of the shoe desired to be softened, usually the toe and vamp.

My device may be fastened to a frame of the machine on which the operator is working, or other support, by means of bolts or screws through holes S, and by means of the swivel joint G, and the tube H, and the adjustable smaller tube I, sliding back and forth into tube H, and by the steam tight joint L, and by a handle R, which is permanently affixed to a part of swivel joint J, the operator is enabled to more conveniently turn the form K, into any desired position while the shoe is in the machine upon which he is operating, thereby applying it to the box toe, or vamp thereof, and conveying the steam to the box toe or vamp, softening the same, and making it pliable while the operator is simultaneously lasting the heel seat.

If desired interchangeable parts K, of suitable form may be provided, varying in size in accordance with the varying sizes of the work sought to be softened.

I prefer to form this applying or spraying member K of substantially U-shaped form, so as to supply the tempering steam to the box toe portion of the shoe around substantially its entire periphery, thus enabling the steam to impinge at a plurality of points on the toe portion at a uniform temperature, and force, from which points it flows over the whole toe. The greater softness, however, is necessary at the edge portion, where the upper material, leather, lining, and box, are lasted and pleated or pulled over the edge of the insole in the subsequent toe lasting operation, and this edge portion is therefore treated to the greater softening action.

It will be noted that a cover is shown in Fig. 1, affixed to the separator by the screws P, and this is made steam tight by sheet packing T, shown in Fig. 2, the top view of the invention; or in any other suitable manner.

The construction and operation will be readily understood from the foregoing description taken in connection with the drawings and it will be seen that the box toe or vamp is softened and made pliable in an easy and efficient manner, while the opera-

tor may be operating upon another part of the shoe.

Having fully described my invention, what I claim as new and desire to secure by Letters Patent, is:—

1. An apparatus of the kind described, comprising means to apply tempering and moistening steam to the toe portion of a boot or shoe, preparatory to lasting, including a steam separator, a U-shaped perforated tubular applying member and a swivel joint connection between said steam separator and said applying member.

2. An apparatus of the kind described, adapted to be mounted in combination with a lasting machine, comprising means to apply tempering and moistening steam to the toe portion of a boot or shoe, preparatory to lasting, including a steam separator, a U-shaped perforated tubular applying member and a swivel joint connection from said steam separator to said applying member, whereby said applying member may be swung into position to operate on the toe portion of a shoe in said lasting machine.

3. An apparatus of the kind described, adapted to be mounted in combination with a lasting machine, comprising adjustable means arranged to be mounted upon a lasting machine to supply steam to the toe portion of a shoe in said lasting machine, comprising a U-shaped member to fit about the toe portion, and a swivel and extensible joint connection between said U-shaped member and a source of steam supply.

4. In an apparatus of the kind described, means to supply tempering and moistening steam to the toe portion of a boot or shoe preparatory to lasting, consisting of a U-shaped perforated tubular applying member adapted to supply heated fluid to soften the edge portion of the shoe upper materials about the toe, and mechanism to permit said applying tool to be swung into or out of operative position with relation to the shoe.

5. An apparatus of the kind described, comprising a removable U-shaped applying member, shaped to fit the shoes being operated upon, and adapted to supply steam to the toe portion of a boot or shoe preparatory to lasting, a steam separator to dry steam to be supplied to said applying member, and a swivel and extensible joint connecting said steam separator and said applying member.

In testimony whereof, I have signed my name to this specification in the presence of two subscribing witnesses.

GEORGE M. FITZPATRICK.
